MULTIPLE CLUTCH MECHANISM

Berthel F. Madsen, Chicago, Ill., assignor to Teletype Corporation, Chicago, Ill., a corporation of Delaware

Original application April 20, 1938, Serial No. 203,021. Divided and this application December 26, 1939, Serial No. 310,938

11 Claims. (Cl. 192—48)

This invention relates to printing telegraph apparatus and particularly to clutch mechanisms through which power is transmitted for performing various operations in the printing telegraph apparatus.

This application is a division of copending application Serial No. 203,021, filed April 20, 1938, by Berthel F. Madsen.

An object of the invention is to divide the performance of functional operations in a printing telegraph apparatus between two cam assemblies supported by a single driving shaft but independently driven thereby in overlap relation.

The invention features an arrangement for driving the operating cams of a printing telegraph receiving unit in which there is a plurality of cam assemblies carried by a driving shaft, one of the cam assemblies including cams for performing certain operations, and in addition a cam for controlling a pawl and ratchet combination through which rotation is imparted by the driving shaft to the other cam assembly. In the copending application of Berthel F. Madsen above identified and also in Patent No. 2,247,408 to Albert H. Reiber there is disclosed a type wheel printer in which the present invention is adapted to be employed. According to the disclosures of the above-identified application and patent the type wheel is slidably mounted upon the type wheel shaft and is supported by a shiftable frame, the normal position of which is such that the entire type wheel is held below the level at which printing is to be effected so that a line which is being printed, including the last character, shall be visible. For each cycle of operation of these receiving units the type wheel supporting frame is oscillated so as to bring the type wheel into printing position before the printing operation occurs and to restore it to normal position after the printing of the character has been accomplished. The type wheel supporting frame is moved by a cam to bring the type wheel into printing position before the printing operation and is restored to normal position under the control of a cam. The cam which elevates the type wheel to printing position imparts sufficient motion to bring the type wheel above the uppermost of its printing positions. A plurality of stop elements are provided, one for arresting the type wheel in each of the elevational positions from which it may be desired to effect printing. The several stop elements are rendered effective alternatively by the shift and unshift function mechanism of the receiv-

ing units, so that these function mechanisms, instead of shifting the type wheel to the desired position as has been the custom in some kinds of printing telegraph apparatus, merely operate to arrest the type wheel in the desired position. The type wheel elevating mechanism includes a yield instrumentality, so that the type wheel may be arrested short of the uppermost position while permitting the elevating cam and part of the elevating mechanism to operate as if imparting full movement to the type wheel.

In the patent to Albert H. Reiber the cam which elevates the type wheel supporting frame is included in a cam assembly which is carried by a power driven shaft and to which rotation is imparted from the shaft through a clutch mechanism, and the cam which controls the lowering of the type wheel supporting shaft following printing is included in a cam assembly which is carried by a separate and distinct power driven shaft and to which rotation is imparted from the shaft through a separate and distinct clutch mechanism.

According to the present invention both of the cam assemblies; namely, the one which includes the cam for elevating the type wheel supporting frame and the one which includes the cam for controlling the lowering of the frame have been mounted on one power driven shaft to receive rotation independently from that shaft. Individual positive clutch mechanisms are provided for connecting the two cam assemblies to the supporting shaft individually. The clutch through which rotation is imparted to the cam assembly which includes the cam for elevating the type wheel supporting frame is tripped in timed relation to the operation of the signal receiving mechanism of the printing telegraph apparatus. The clutch through which rotation is imparted to the other cam assembly is tripped in timed relation to the operation of the first cam assembly and may, if desired, be tripped by that cam assembly.

For a complete understanding of the invention reference may be had to the following detailed description to be interpreted in the light of the accompanying drawing, wherein

Fig. 1 is a perspective view of the preferred embodiment of the invention wherein two operating cam assemblies are carried by a single driving shaft and are independently driven therefrom, affording the possibility of nearly a full cyclic interval of lag of one cam assembly behind the other cam assembly;

Fig. 2 is an elevational view partly in section of the apparatus shown in Fig. 1;

Fig. 3 is a plan view of the mechanism shown in Figs. 1 and 2;

Fig. 4 is an elevational view partly in section of an alternative arrangement of operating cam assemblies wherein two cam assemblies are carried by a single driving shaft and are independently driven therefrom, the arrangement affording only a fractional cyclic lag one cam assembly behind the other cam assembly; and

Fig. 5 is a plan view of the apparatus shown in Fig. 4.

Referring to Figs. 1, 2, and 3 the reference numeral 11 designates a continuously driven shaft which has secured thereto the driving element 12 of a positive drive clutch mechanism, the driven element of which, indicated 13, is slidably axially of shaft 11. Driven element 13 is urged by compression spring 14 into engagement with driving element 12 and is normally held disengaged from driving element 12 by clutch throwout lever 16 which engages the upwardly projecting cam portion 15 of a flange 20 integral with driven clutch element 13. Flange 20, with the exception of cam portion 15, is clear of and entirely below the end of clutch throwout lever 16 even when the clutch elements are engaged, so that spring 25 which biases the lever 16 counterclockwise, as viewed in Figs. 1 and 3, may restore the free end of lever 16 to engagement with the peripheral surface of driven clutch element 13 after the tripping of lever 16. However, cam portion 15 of flange 20 revolves in the path of the free end of lever 16, and when it encounters the end of the lever, the driven element 13 is moved downwardly due to the upwardly sloping cam contour, thus moving driven element 13 axially away from driving element 12. Clutch throwout lever 16 may be arranged to be tripped by any desired timing means such as the selector cam assembly of a printing telegraph apparatus, whereby the tripping of the clutch comprising elements 12 and 13 may be timed to the reception of signals. Driven clutch element 13 is keyed to a cam assembly sleeve 17 which may have secured thereto the cam for elevating the type wheel supporting frame shown in the hereinbefore identified copending application and the sleeve 17 may include other function performing cams as desired, as will presently be set forth. For the sake of simplicity in the drawing such cams have been excluded from the showing of Figs. 1 and 2. Cam assembly sleeve 17 has secured thereto a cam which is shown in the drawing and is identified 18, the function of which is to set in operation a second cam assembly which will now be described.

Below the cam assembly sleeve 17 but having no direct connection therewith, a ratchet 19 is secured to shaft 11. Below the ratchet 19 a disc 21 is supported on shaft 11 so as to be capable of remaining stationary while shaft 11 is rotating. Disc 21 carries a pivoted pawl 22 which is urged by a leaf spring 23 into engagement with ratchet 19. Adjacent to the point at which pawl 22 is pivotally mounted disc 21 is provided with an indentation 24 in the periphery thereof which is of sufficient depth that when pawl 22 engages ratchet 19 the tail of pawl 22 swings out over a portion of the indentation. A pawl controlling lever arm 25 is pivotally supported at 27 and is biased in clockwise direction as viewed in Figs. 1 and 3 by spring 28 which is considerably stronger than leaf spring 23, so that lever arm 26 may

hold pawl 22 disengaged from ratchet 19 in opposition to spring 23.

Below the disc 21 a cam 31 is rotatably mounted on shaft 11 so that the cam may be withheld from rotation while shaft 11 is rotating. Disc 21 is provided with an arcuate slot 32, and a clamping screw 33 passes through slot 32 and threadedly engages cam 31 for adjustably securing the cam to disc 21. Spring biased bail 34 which may be any element that is to be operated by cam 31 such as, for example, a bail for controlling the lowering of the type wheel supporting frame or a printing bail, supports at its free end a follower roller 36 which engages the periphery of cam 31.

The retention of cam 31 in rest or idle position is accomplished by the free edge of pawl controlling lever arm 26 which engages the innermost portion of indentation 24 in disc 21, thus serving as a detent for disc 21 and cam 31, and engaging the tail of pawl 22 to hold it out of engagement with ratchet 19. The clamping screw 33 and slot 32 afford a wide range of adjustment of cam 31 with respect to disc 21 so that the rest position of cam 31 may be varied and the desired relation between cam 31 and its follower roller 36 established. Cam 18, carried by cam assembly sleeve 17, has a portion of sufficient radius, as indicated in dotted lines in Fig. 3, to rock lever arm 26 counterclockwise, whereupon the restraint upon pawl 22 is released and spring 23 rocks it into engagement with ratchet 19. Cam 18 may be positioned on sleeve 17 so as to rock lever arm 26 free of pawl 22 at any time during a cycle of rotation of sleeve 17, the only limitation being that in its position of arrestment it shall not permit pawl 22 to engage ratchet 19, whereby cam 31 would be rotated continuously.

As soon as pawl 22 is brought into engagement with a tooth of ratchet 19, which rotates continuously with shaft 11, rotation is imparted to disc 21 and therefore to cam 31. Pawl 22 thus moves out of range of pawl controlling lever arm 26, which in turn is maintained in extreme counterclockwise position by riding against the periphery of disc 21. During the rotation of cam 31, cam sleeve 17, controlled by clutch throwout lever 16, may remain at rest or may be released for rotation as a result of the reception of another signal combination by the printing telegraph apparatus. As cam 31 completes a cycle of operation the free end of lever arm 26 enters indentation 24 in the periphery of disc 21, rocks pawl 22 out of engagement with ratchet 19 and, operating as a detent, arrests disc 21 and cam 31. With this arrangement a plurality of cam assemblies may be carried and driven by a single driving shaft with only slightly less than 360 degrees of cyclic lag of cam 31 behind cam assembly sleeve 17, or with any lesser amount of lag. It will be understood that any desired additional cams may be included on the cam assembly sleeve 17 such as a signal transferring cam and that any desired additional cams may be assembled to the cam 31 and driven therewith such as printing and function performing cams.

The cam driving mechanism shown in Figs. 4 and 5 has some features in common with the mechanism shown in Figs. 1 to 3 inclusive but differs therefrom in that the maximum cyclic lag of one cam assembly behind the other is relatively limited. Reference numeral 41 designates a rotatable shaft to which is secured a driving gear 42. Shaft 41 also has secured thereto the driving element 43 of a positive clutch mecha-

nism which includes a driven element 44 normally restrained from engagement with driving element 43 by clutch throwout lever 46. Compression spring 47 urges driven element 44 to engage driving element 43. Driven element 44 is slideable upon shaft 41 and is keyed to a cam assembly sleeve 48 so that when clutch throwout lever 46 is tripped, cam sleeve 48 and the cams secured to it are released for a cycle of rotation. Below cam sleeve 48 shaft 41 has secured thereto a ratchet 49. Between the ratchet 49 and the gear 42 a cam 51 is rotatably supported on shaft 41 so that it may be held stationary while shaft 41 is rotating. Cam 51 has pivotally mounted thereon a pawl 52 which is biased by spring 53 for clockwise movement into engagement with ratchet 49. Pawl 52 has secured thereto upstanding pin 54 which is of sufficient height to engage the periphery of a cam 56 carried by cam sleeve 48. Cam 56 performs the same function as cam 18 in Figs. 1 to 3 inclusive; namely, it sets in rotation cam 51 and any desired additional cams that may be associated with cam 51, as appears by the following description.

In the normal or idle condition of the apparatus shown in Figs. 4 and 5, the clutch comprising elements 43 and 44 is in disengaged condition, cam sleeve 48 is therefore stationary, and in order that cam 51 may also be stationary, pin 54 carried by pawl 52 is engaging the outermost portion of the periphery of cam 56 whereby pawl 52 is held out of engagement with ratchet 49. Upon the tripping of clutch throwout lever 46, cam sleeve 48 is set in rotation. After rotating through a predetermined angle, cam 56 presents a descending slope to pin 54, whereby pawl 52 is permitted to come into engagement with ratchet 49 and rotation is imparted to cam 51. Cams 56 and 51 then rotate at the same angular velocity until driven clutch element 44 is disengaged from driving clutch element 43 by clutch throwout lever 46. Upon the arrestment of cam 56, pin 54 carried by pawl 52 is carried forward with respect to cam 56 and ascends the slope which it had previously descended, thus withdrawing pawl 52 from engagement with ratchet 49 and terminating the rotation of cam 51. It will be apparent that there can be relative rotation between cams 56 and 51 only while pin 54 is descending from and ascending to the outermost portion of the periphery of cam 56. This is due to the fact that when pawl 52 has been withdrawn from engagement with ratchet 49, no further rotation can be imparted to cam 51 by the ratchet, and when pawl 52 has moved into engagement with ratchet 49, cams 56 and 51 rotate together without relative motion therebetween.

The apparatus shown in Figs. 4 and 5 has particular utility where it is desired to time the performance of an operation such as, for example, the operation of a print bail just after the completion of a cycle of operation of some other function performing cam assembly such as, for example, a cam assembly which includes a transfer cam. As shown in Fig. 5 the bail 57 to be operated by cam 51 may be provided at its free end with a cam follower roller 58 which engages the periphery of cam 51. Bail 57 may, for example, control printing by overtravel as disclosed in the hereinbefore identified application of Albert H. Reiber, the printing operation occurring as cam follower roller 58 travels down the sharp descent in the periphery of cam 51. When the overtravel printing mechanism includes a yield spring as in the embodiment disclosed in

the patent to Albert H. Reiber it is not necessary to retract bail 57 immediately from its innermost position with respect to cam 51 and therefore bail 57 may be permitted to serve as a detent for cam 51 to restrain it from responding to any torque which may be imparted to it by shaft 41 due to friction.

Bail 57 may also be employed to increase the cyclic lag between cams 56 and 51. Such increase may be accomplished by timing the apparatus so that the cam 56 shall disengage pawl 52 from ratchet 49 at about the instant that follower roller 58 encounters the top of the descent of cam 51. The spring biased bail 57 will then impart a torque to cam 51 due to engagement of follower roller 58 with the descending slope, and pin 54 may thus be carried a few additional degrees of angle along the periphery of cam 56. When thereafter cam 56 is set in operation it will rotate through a greater angular distance before pawl 52 engages ratchet 49 than it would had cam 51 been arrested immediately upon disengagement of pawl 52 from ratchet 49.

Although specific embodiments of the features of invention have been disclosed and described herein it will be understood that the invention is not limited to such specific embodiments but is capable of modification, reorganization, rearrangement, and substitution of parts and elements without departing from the spirit of the invention and within the scope of the appended claims.

What is claimed is:

1. In a printing telegraph apparatus, a power driven shaft, a cam assembly member carried by said shaft, means for establishing a driving connection between said shaft and said cam assembly member, a cam assembly carried by said shaft, a ratchet fixed to said shaft, a pawl carried by said cam assembly, means associated with said cam assembly member for conditioning said pawl to become engaged with said ratchet for one revolution of said pawl incident to each revolution of the cam assembly member, and means for engaging said pawl with said ratchet whereby rotation is imparted to said cam assembly.

2. In a printing telegraph apparatus, a power driven shaft, a cam assembly member carried by said shaft, means for establishing a driving connection between said shaft and said cam assembly member, a cam assembly carried by said shaft, means for establishing a driving connection between said shaft and said cam assembly, and means supported by said cam assembly member and said cam assembly for controlling the second mentioned driving connection means.

3. In a printing telegraph apparatus, a power driven shaft, a cam assembly member carried by said shaft, means for establishing a driving connection between said shaft and said cam assembly member, a cam assembly carried by said shaft, means for establishing a driving connection between said shaft and said cam assembly, and means carried by the cam assembly member for controlling the enablement and disablement of the last mentioned means.

4. In a power transmitting device, a power driven shaft, a plurality of elements carried by said shaft to be individually driven thereby, a plurality of clutch mechanisms carried by said shaft for imparting rotation to said elements individually, means for initiating engagement of one of said clutch mechanisms, and means associated with the element rotated thereby and operable during its rotation for initiating engage-

ment of the other clutch mechanism for one revolution incident to each revolution of the first initiated clutch mechanism.

5. In a power transmitting device, a power driven shaft, a plurality of elements carried by said shaft to be individually driven thereby, a plurality of clutch mechanisms carried by said shaft for imparting rotation to said elements individually, means for initiating engagement of one of said mechanisms, means for controlling the initiation of engagement of the other of said clutch mechanisms and for determining the rest position of the element driven thereby, and means associated with the element rotated by said one clutch mechanism for actuating the last mentioned means.

6. In a power transmitting device, a power driven shaft, a cam assembly member carried thereby, a spring loaded clutch mechanism for imparting rotation from said shaft to said cam assembly member, a ratchet secured to said shaft, a cam assembly carried by said shaft, a pawl carried by said cam assembly for engagement with said ratchet, means for normally holding said pawl disengaged from said ratchet, means for tripping said spring loaded clutch mechanism to impart rotation to said cam assembly member, and means included in said cam assembly member for disengaging said holding means from said pawl for permitting engagement of said pawl with said ratchet.

7. In a power transmitting device, a power driven shaft, a cam assembly member carried thereby, a spring loaded clutch mechanism for imparting rotation from said shaft to said cam assembly member, a ratchet secured to said shaft, a cam assembly carried by said shaft, a disc coaxial with and adjustably secured to cam assembly, a pawl carried by said disc for engagement with said ratchet, means engaging the periphery of said disc for normally holding said pawl disengaged from said ratchet, means for tripping said spring loaded clutch mechanism to impart rotation to said cam assembly member, and means included in said cam assembly member for disengaging said holding means from said pawl for permitting engagement of said pawl with said ratchet.

8. In a power transmitting device, a power driven shaft, a cam assembly member carried thereby, a spring loaded clutch mechanism for imparting rotation from said shaft to said cam assembly member, a ratchet secured to said

shaft, a cam assembly carried by said shaft, a disc coaxial with and adjustably secured to said cam assembly having an indentation in the periphery thereof, a pawl pivotally supported by said disc for engagement with said ratchet, said pawl having an arm extending out over a portion of the indentation in said disc when the pawl is in engagement with the said ratchet, means engaging the periphery of said disc for withdrawing said pawl from engagement with said ratchet upon entrance of the means into said indentation, means for tripping said spring loaded clutch mechanism to impart rotation to said cam assembly member, and means included in said cam assembly member for disengaging said withdrawing means from said pawl for permitting engagement of said pawl with said ratchet.

9. In a power transmitting device, a power driven shaft, a cam assembly member carried thereby, a clutch mechanism for imparting rotation from said shaft to said cam assembly member, a ratchet secured to said shaft, a cam assembly carried by said shaft, a pawl pivotally supported by said cam assembly for engagement with said ratchet, and means associated with said cam assembly for normally holding said pawl disengaged from said ratchet.

10. In a power transmitting device, a power driven shaft, a cam assembly member carried thereby, a spring loaded clutch mechanism for imparting rotation from said shaft to said cam assembly member, a ratchet secured to said shaft, a cam assembly carried by said shaft, a pawl pivotally supported by said cam assembly for engagement with said ratchet, and means associated with said cam assembly for normally holding said pawl disengaged from said ratchet.

11. In a power transmitting device, a power driven shaft, a plurality of elements carried by said shaft to be individually driven thereby, a plurality of clutch mechanisms carried by said shaft for imparting rotation to said elements individually, means for controlling engagement of one of said clutch mechanisms, and means associated with the element rotated thereby and operable during its rotation for controlling the actuation of the other clutch mechanism for one revolution incident to each revolution of the first controlled clutch mechanism.

BERTHEL F. MADSEN.
